his attorney.

UNITED STATES PATENT OFFICE.

ALBERT L. GRAY, OF ST. LOUIS, MISSOURI.

DESIGN FOR A SHIELD FOR SYRINGES.

SPECIFICATION forming part of Design No. 27,638, dated September 14, 1897.

Application filed July 3, 1897. Serial No. 643,456. Term of patent 14 years.

To all whom it may concern:

Be it known that I, ALBERT L. GRAY, a citizen of the United States of America, residing at St. Louis, State of Missouri, have invented and produced a new and original Design for Shields or Pads for Syringes; and I do hereby declare the following to be a full, clear, and exact description of the same, reference being had to the accompanying drawings, forming 10 a part thereof.

Figure 1 shows a perspective view of my new and original design for a shield or pad for syringes. Fig. 2 is a sectional view taken through the longest diameter, and Fig. 3 a 15 similar view through the shortest diameter.

The leading feature of my design consists in the pad or shield for syringes, the configuration of the same being such as to provide an elliptical base from which projects a frustum having inverted sides, the center of the frustum being in line with the center of the elliptical base, so that the side walls of the frustum on line with the shortest diameter 20 will join the upper face of the base, so as to provide thereon side walls of increased thickness, the perimeter of the elliptical base inclining.

A represents the elliptical base, the edge or perimeter thereof inclining, as shown at $a a$, the ends of the elliptical base being practically flat or provided with parallel walls for a short distance from the ends. From the base projects a hollow frustum B, having inverted sides, and the side walls join the base, so that at the shortest diameter of the base the 35 side edges will present a thickened portion, the greatest thickness being at the center.

The pad of the configuration herein described presents a smooth exterior and an aperture which extends through the central portion of the pad, as is fully shown in Figs. 2 and 3 of the drawings.

Having described my invention, what I claim as new, and desire to secure by Letters Patent, is—

The design for a shield or pad for syringes herein shown and described.

In testimony whereof I affix my signature in presence of two witnesses.

ALBERT L. GRAY.
